UNITED STATES PATENT OFFICE.

WILLIAM W. WADSWORTH, OF TREMONTON, UTAH.

BOX-SEALING DEVICE.

Application filed October 13, 1925. Serial No. 62,324.

This invention relates to box sealing devices and has relation more particularly to a device of this kind especially designed and adapted for use in closing the ends of cartons, and it is an object of the invention to provide a device of this kind which in its structure comprises no levers, eccentrics or the like.

Another object of the invention is to provide a device of this kind comprising a platform and a box or carton holder pivotally supported thereby and which, when swung below the platform, coacts with such platform to impose sufficient tension upon the closed end flaps of a carton or the like upon the holder to assure requisite effective gluing of said flaps to close an end of the carton.

A further object of the invention is to provide a device of this kind wherein the holder or holders comprised therein, when not in use, are substantially confined below the platform and thus permitting the platform to be employed without hindrance or obstruction for other purposes, such as gluing, stencil work and the like.

The invention consists in the details of construction and in the combination and arrangement of the several parts of my improved box sealing device whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a box sealing device constructed in accordance with an embodiment of my invention;

Figure 2 is a sectional view taken substantially on the line 2—2 of Figure 1;

Figure 3 is a fragmentary view in perspective of a holder showing a carton initially applied;

Figure 4 is a view similar to Figure 3 showing the flaps at an end of the carton partly folded;

Figure 5 is a sectional view taken substantially on the line 5—5 of Figure 1;

Figure 6 is a sectional view taken substantially on the line 6—6 of Figure 1;

Figure 7 is a view in perspective of one of the holders unapplied.

As disclosed in the accompanying drawings, P denotes a platform of desired configuration and dimensions but herein disclosed as of a material length and rectangular in design, said platform being maintained in desired elevation by the supporting legs 1 coating in a conventional manner with the longitudinal marginal portions thereof.

The legs 1 at one side of the platform P are transversely aligned with the legs at the opposite side and the lower portions of each pair of transversely aligned legs 1 are tied or connected by the cross members or beams 2. Disposed through the opposite end portions of these cross members or beams 2 and at desired points inwardly of the legs 1 are the bars or pipes 3 extending longitudinally of the platform P and substantially the entire length thereof, said rods or pipes 3 providing mountings for the holders H.

Each of the holders H comprises a top or table 4 of a size and configuration to conform to the interior dimensions of the end of a carton to be closed and depending from the sides of said top or table 4 and at right angles thereto are the side plates 5 the forward margins of which being downwardly and rearwardly inclined toward the elongated arms 6 the rear edges of which being flush with the rear edge of the top or table 4. The lower portions of the arms 6 are freely mounted on a rod or pipe 3 whereby the holder is supported for swinging movement in a vertical direction,

the mountings for the holder being so positioned of the arms that the top or table 4 closely approaches the under surface of the platform P when the holder is in upright vertical position, such space a being substantially equal to the overlying or overlapping end flaps F of a carton C to be glued in closed assembly. Furthermore, it is to be noted that the rod or pipe 3 is positioned inwardly from the adjacent longitudinal margin of the platform P to have the for-

ward edge of the top or table 4 substantially flush with the adjacent longitudinal edge of the platform P when the holder is in its vertical upright position.

5 The arms 6 of the holder H are tied or connected by the bracing or reinforcing members 7 preferably positioned above and below the rod or pipe 3.

10 As herein disclosed, a battery of three holders H is positioned between each pair of adjacent longitudinally spaced supporting legs 1 although, if desired, this number may be either increased or decreased. Furthermore, it is to be noted that in the 15 assembly as disclosed in the accompanying drawings, the holders H are disposed along both longitudinal marginal portions of the platform P to assure a maximum output from a single device.

20 It is to be observed that when not in use the holders will be raised to a substantially vertical upright position and at which time they are substantially entirely confined below the platform P and thus permit such 25 platform to be readily and conveniently employed for table purposes such as for gluing operations, stenciling and the like. The construction of the holders H is such to offer a minimum of hindrance or obstruction to the platform P when used for 30 table purposes.

As is well known, cartons employed in the packing of can goods or the like are received by the packer in flattened form 35 with the end flaps free. With the use of my present device, a holder H is swung outwardly and a carton C formed therearound and the flaps F at one end of the carton C folded into overlying or overlapping relation 40 down upon the table or top 4 of the holder, glue or other adhesive having been first properly applied to the flaps. The holder is then swung forwardly to its substantially vertical upright position bringing 45 the overlying or overlapping end flaps F between the platform P and the top or table 4 of the holder, the space a between said table or top 4 and platform P being such as to assure an effective tension or 50 pressure being imposed upon the overlying or overlapping flaps F to assure an effective gluing or adhesive connection between such flaps. After the glue or other adhesive has properly set, the holder is swung 55 outwardly and the carton with its sealed end is removed therefrom.

Connecting the central portions of the cross members or beams 2 is an elongated member or beam 8 and bolted or otherwise 60 attached to said member or beam 8 at points spaced lengthwise thereof are the elongated spring members 9. Each of the springs 9 extends beyond opposite sides of the member

or beam 8 and each extended end portion has contact from below with a cross rod 65 10 connecting the lower end portions of the arm 6, said spring 9 imposing sufficient tension to urge the top or table 4 upwardly for proper coaction with the platform P as hereinbefore referred to.

70 To facilitate the functioning of the springs 9, the arms 6 are provided with the elongated openings 11 through which a bar or pipe 3 is directed. When it is desired to drop a table or top 4 it is only necessary to step upon the coacting outer end portion of a spring 9 and the desired fall of the top or table 4 as afforded by the slots 11 will occur by gravity.

75 From the foregoing description it is thought to be obvious that a box sealing device constructed in accordance with my invention is particularly well adapted for use by reason of the convenience and facility with which it may be assembled 80 and operated, and it will also be obvious that my invention is susceptible of some change and modification without departing from the principles and spirit thereof and for this reason I do not wish to be 85 understood as limiting myself to the precise arrangement and formation of the several parts herein shown in carrying out my invention in practice except as hereinafter claimed.

90 I claim:—

1. In combination with a platform, a carton holder comprising a table, depending plates carried by the sides of the table, arms extending from the plates, said arms having elongated openings, a member disposed through the openings in the arms to support the arms for swinging movement, said arms having lengthwise movement to the extent afforded by the openings, a cross member connecting the arms, and a spring contacting with said cross member from below for urging the arms upwardly.

100 2. In combination with a platform and a supporting structure therefor, a carton holder comprising a table, depending plates carried by the sides of the table, arms extending from the plates, a bar carried by the supporting structure for the platform, said arms having elongated openings 105 through which said bar extends to provide a pivotal mounting for the arms, the openings in the arms permitting said arms to have limited lengthwise movement, a member connecting the arms, and an elongated spring carried by the supporting structure for the platform and contacting with the connecting member from below.

110 In testimony whereof I hereunto affix my signature.

115 WILLIAM W. WADSWORTH.
